MOBILE HOME HITCH COYER

Lloyd R. Hershberger, Rte. 1, Bremen, Ind. 46506

Filed Oct. 4, 1973, Ser. No. 403,529

Term of patent 7 years

Int. Cl. D12—10

U.S. Cl. D12—162

Fig. 1

Fig. 2

Fig. 3

Fig. 4

Fig. 5

Fig. 6

Fig. 7

FIG. 1 is a perspective view of a mobile home hitch cover showing my new design;

FIG. 2 is a top plan view thereof;

FIG. 3 is a side elevational view thereof opposite to that shown in FIG. 1;

FIG. 4 is a front elevational view thereof;

FIG. 5 is a rear elevational view thereof;

FIG. 6 is a bottom plan view thereof; and

FIG. 7 is a sectional elevational view thereof taken along the line 7-7 in FIG. 5.

I claim:

The ornamental design for a mobile home hitch cover, substantially as shown.
